(57) **CLAIM**

The ornamental design for a robot, as shown and described.

DESCRIPTION

FIG. 1 is a front perspective view of a robot showing our new design;

FIG. 2 is a front view thereof;

FIG. 3 is a rear view thereof;

FIG. 4 is the left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 1;

FIG. 10 is an enlarged view of the encircled portion 10 in FIG. 1;

FIG. 11 is an enlarged view of the encircled portion 11 in FIG. 2;

FIG. 12 is an enlarged view of the encircled portion 12 in FIG. 3;

FIG. 13 is an enlarged view of the encircled portion 13 in FIG. 4;

FIG. 14 is an exploded view thereof showing a state of use where the hand feature is detached from the arm of the robot, and the arm is shown folded and inserted into the body of the robot; and,

FIG. 15 is another front perspective view thereof showing a state of use where the arm of the robot is folded and inserted into the body of the robot, and the body is then rotated 180 degrees.

The evenly-dashed broken lines in the drawings depict portions of the robot that form no part of the claimed design. The dot-dot-dashed broken lines encircling portions of the claimed design that are illustrated in enlargements form no part of the claimed design.
